UNITED STATES PATENT OFFICE

JEAN ALBERT SOUSTRE, OF CENDRIEUX, FRANCE

KNIFE ADAPTED FOR MULTIPLE USES AND COMPRISING A MONKEY WRENCH

Application filed June 6, 1928, Serial No. 283,285, and in France December 13, 1927.

The present invention relates to a knife adapted for multiple uses with which is combined a monkey wrench in such manner as to form a compact device of size and weight that 5 it may be readily carried in the pocket.

For this purpose the middle partition of the knife is made in a single piece of cast or wrought steel, and the head of the said wrench is disposed at one end. In this manner not only the middle partition but also the 10 whole knife forms the handle of the monkey wrench and does not cause an increase of the thickness of the knife.

The appended drawings show by way of 15 example an embodiment of the invention.

Fig. 1 is a front elevation of the knife.

Fig. 2 is the corresponding side view.

The said knife is constructed in the known manner by two outer plates 1 and a middle 20 plate 2 which are connected together by rivets 3—4—5—6 with the interposition of the spacing members 7.

The rivet 3 also serves as the pivot axle 25 for a knife blade 8 and a screwdriver 9, for instance, and the rivet 4 serves as an axle for a cork-screw 10 and a punch 11. The middle plate 2, consisting of cast or wrought steel, is formed in one with the main body 30 of a monkey wrench 12 which is operated by making use of the knife handle. In order that the plate of the monkey wrench presents the maximum of solidity the shoulder 13 of the monkey wrench will be preferably caused to bear against the spacing members 7 and 35 will be suitably cut out for this purpose. The said device thus forms a very portable outfit which will be of great service to users of bicycles, motorcycles, automobiles, or to other persons, who are thus provided, without 40 opening a tool bag or box, with the principal tools for making small repairs.

Neither the size nor the weight of the knife are appreciably increased, and it can be readily carried in the pocket.

45 Obviously, the invention is not limited to the aforesaid form of construction which is given by way of example, and in particular, the number and character of the tools disposed in the knife may be as desired.

50 Claim:

The combination in a pocket knife having two compartments, a middle partition adapted to separate the two compartments and carrying at one of its ends a monkey wrench in one piece with the said partition, two outer 55 walls for closing the compartments externally, spacing members at both ends of the said compartments, the head of the said monkey wrench being provided with shoulders on both sides, these shoulders being 60 adapted to bear on the said spacing members at the corresponding end of the knife.

In testimony whereof I have hereunto affixed my signature.
